LESLIE STEVENS, OF GLEN RIDGE, NEW JERSEY.

HAT-BLOCK.

1,258,718.

Specification of Letters Patent. Patented Mar. 12, 1918.

Application filed July 13, 1911, Serial No. 638,283. Renewed January 4, 1918. Serial No. 210,375.

To all whom it may concern:

Be it known that I, LESLIE STEVENS, a citizen of the United States, residing at Glen Ridge, county of Essex, and State of New Jersey, have invented certain new and useful Improvements in Hat-Blocks, fully described and represented in the following specification and the accompanying drawings, forming a part of the same.

10 This invention relates to blocks or forms for shaping hat crowns having straight sides meeting the tip at a sharp edge, and more particularly for shaping crowns of so-called square crown hats, that is, hats having 15 crowns which have a flat top or tip and straight sides perpendicular to the tip. The invention has been made especially with the idea of providing a block for use in shaping the crowns of straw hats.

20 With the blocks heretofore used it has been impossible to shape a straw hat with a very sharply defined edge at the angle between the tip and the sides of the crown, and with the sides extending straight from such edge 25 all the way to the brim, and, in a square crowned hat, perpendicular to the tip, or so nearly so that the variation from the desired shape is not noticeable. This is due largely to the characteristic quality of the straw 30 which makes it impossible to shape the hat so that it will retain exactly the form of the block when removed therefrom, and to the custom and practical necessity of making the crown and brim of the hat separately

35 and securing them together by sewing or otherwise fastening the upturned inner portion of the brim part to the band or lower part of the sides of the crown. Instead of having the desired shape, therefore, finished 40 hats of this kind, as heretofore made, have had a more or less rounded edge between the tip and the sides, and the sides, particularly at their upper and lower portions adjacent to the tip and the brim have bulged outward more or less. The object of the present 45 invention is to provide a block by the use of which straw hats may be shaped with a clearly defined sharp edge between the sides and the tips and with the sides of the crown 50 extending straight without any bulge or deviation from the tip to the base, and especially with square crowns having the desired straight sides perpendicular to the tip; and these results are secured by the invention, at least with such an approach to abso-

lute accuracy that any variation is not perceptible.

With these objects in view, a block for shaping square crown hats and embodying the various features of the invention is shaped with the sides substantially perpendicular to the plane of the tip throughout the greater extent of the height of the block, and with a short, sharp outward flare at the tip to join the tip face of the block at an acute angle, and with the lower or band portion of the sides inclined slightly inward, and with its tip surface made slightly concave. While the sides of blocks for shaping square crown hats may be made exactly perpendicular to the plane of the tip throughout the greater portion of the height of the block, the best effect in a square crown hat is secured by shaping the block so that this straight portion of the sides will be very slightly outwardly inclined toward the tip. In order that the tip edge may have greater strength and resistance to wear it is made of metal, such metal edge being best provided by setting an edge ring or band into the material of which the main body of the block is made. The base of the block may also be provided with a metal edge.

A full understanding of the invention can best be given by a detailed description of a block embodying the various features thereof, and such a description will now be given in connection with the accompanying drawings.

In said drawings, Figure 1 shows in side elevation, and Fig. 2 shows in side elevation looking in the direction at right angles to Fig. 1, a block for shaping a square crown hat, portions being broken away to show the sunken tip face and the metal ring set into the block to provide the metal tip edge. The block may be of any desired proportions and may be of any suitable material and construction. The usual material from which blocks of this kind are made is wood, and the block will, because of its greater circumferential size at the tip than at the base, best be of sectional construction to permit of its being removed from the shaped hat piece by piece. The drawings indicate a three piece block of the construction shown in my application filed July 13, 1911, Serial No. 638,284. The sides of the block throughout the greater portion of its height are straight and substantially perpendicular to

the plane of the tip edge of the block, and, in the block shown and as will usually be the case, to the base of the block. For a short distance adjacent to the tip edge b the sides 5 flare outwardly as shown at a' at an angle to the main straight portion a of the sides and so as to form a noticeably acute angle with the plane of the tip; and the lower or band portion a^2 of the sides are formed to 10 slant inwardly at a slight angle to the main portion of the sides, making a slightly obtuse angle with the lower face or base of the block. While the main portion of the sides of the block must be substantially perpendicular to the plane of the tip edge in order 15 to shape a hat with a true square-shaped crown, it is found that the best results are secured by shaping the sides so that the main straight portion shall slant very slightly 20 outward from the perpendicular from its lower to its upper portion, that is, so that the circumferential size of this straight sided portion of the block shall be just slightly greater near the tip but below the outwardly 25 flared portion a' than it is adjacent to the inwardly slanting base portion of the block.

In using the block, the sharp projecting tip edge provides a support extending into the tip angle of the hat against which the 30 material may be pressed so as to be given a sharp clearly defined edge from which the sides of the hat crown extend straight downward without the usual bulge adjacent to the tip edge, and when the block is of the 35 shape shown for shaping a square crown hat the sides will extend perpendicular to the plane of the tip. It will be noticed that the projecting tip edge of the block shown leaves a relatively recessed portion adjacent there- 40 to. Compression of the straw over this relatively recessed portion of the block under the pressure of the iron or other shaping means employed will be less than immedi- 45ately at the tip angle and over the main por- tion of the sides of the crown of the hat, and the tendency of the straw to bulge out- 50ward at this point will be reduced. The amount of flare to be given to the side of the block adjacent to the tip, and the depth of 55 the resulting relative recess adjacent to the tip, will depend upon the kind of straw of which the hat to be shaped on the block is made. For a heavy straw, the tip edge should project considerable beyond the line 60 of the straight portion of the side as shown. For a lighter straw the tip edge need not, and should not, project so far as for the heavier straw, and for an extremely light and fine straw a very slight projection is 65 sufficient. For such a very light and fine straw, a block for shaping a square crown will give good results if the sides of the block, except for the inwardly inclined band portion, extend straight, but preferably with the slight outward inclination shown in the

drawings, clear up to the tip edge. Even for such a straw, however, a slight projection of the tip edge beyond the line of the main portion of the sides is desirable.

When the brim of a straw hat is secured 70 to a crown in the customary manner of sewing or otherwise securing the upturned inner edge of the brim to the lower or band por- 75 tion of the crown, the double thickness of straw thus resulting at the band of the hat usually causes a more or less outward slant or bulge of this portion of the shaped hat. This is avoided with the block shown since the band portion of the block is, because of its inwardly inclined face a^2 , of such rela- 80 tively reduced size as to accommodate the extra thickness of material and enable the side of the crown to be shaped straight clear down to the brim. For best results, the band portion of the hat is made of rela- 85 tively less circumferential size than the main portion thereof to accommodate the extra thickness of the band portion of the hat by shaping this part of the block to slant off at an angle to the main portion as shown, 90 rather than by shaping the block so as to have an abrupt joining of the face of the band portion with the face of the main portion of the side of the block, as it is found that with anything approaching an abrupt 95 shoulder between these two parts of the side of the block it is difficult if not impossible to shape the side of the hat crown without giving it a noticeable indication of such shoulder.

100

In order that the hat may be shaped with a flat tip without any upward bulge either immediately adjacent to the tip edge or at the center, the tip face c of the block if in- 105 tended for shaping hats of heavy or medium heavy straw is best made slightly concave as shown, so that the tip edge b of the block will project not only outward beyond the main straight portion of the side of the block, but also upward beyond the main por- 110 tion of the tip face of the block.

100

The sharp tip edge of the block formed by faces meeting at an acute angle would be particularly liable to become injured in use if made of wood or other comparatively soft material. To avoid this difficulty in blocks made of wood or other soft material, I make the tip edge part of the block of a suitable hard material such as metal, and this is best done by setting into the material 115 of which the main portion of the block is made a metal band or ring d , which may be secured in place by screws as shown, or in any other suitable manner, and which in a sectional block will be in sections corre- 120 sponding to the sections of the block. This feature of the invention of providing the block with a metal edge while of special ad- 125 vantage in blocks having a sharp edge formed by sides meeting at an acute angle 130

will also be found of advantage and may be employed in other blocks having edges which it is desired shall be resistant to wear and injury; and such metal edge may be provided otherwise than by means of a ring set into the block, as by securing a metal plate to the face of the block such as the plate forming the base face of the block shown in the drawings.

10. What is claimed is:—

1. A hat block for shaping square crown hats, having its sides vertically straight and substantially perpendicular to the plane of its tip face throughout the greater portion 15 of the height of the block and formed to slant slightly outward at the tip beyond the adjacent portion of the vertical sides to meet the tip face at an acute angle.
2. A hat block for shaping square crown hats having its sides formed to flare outwardly at the tip to meet the tip face of the block at an acute angle, having its sides throughout the greater portion of the height 25 of the block substantially perpendicular to the plane of the tip edge, and having the lower portion of the sides formed to slant inward.

3. A hat block for shaping square crown hats having its tip face slightly concave 30 and having its sides formed to flare outwardly at the tip to meet the tip face of the block at an acute angle, having its sides throughout the greater portion of the height 35 of the block substantially perpendicular to the plane of the tip edge, and having the lower portion of the sides formed to slant inward.

4. A hat block having its sides extending straight throughout the greater extent of 40 the height of the block, and having its tip and side faces adjacent to the meeting edges of the faces shaped to slant outwardly to form an acute angled edge to project above the main portion of the tip face of the block 45 and outward beyond the plane of the main portion of the sides of the block.

5. A hat block having its sides extending straight throughout the greater extent of the height of the block, and having the lower or 50 band portion of the sides formed to slant inwardly at a slight angle to the main portion of the sides.

6. A hat block for shaping square crown hats, having its band portion of reduced 55 circumferential size as compared with the adjacent portions of the block.

7. A hat block for shaping square crown hats, having the tip of the block of greater

circumferential size than the band portion thereof, and having the intermediate portion of the block throughout the greater extent of its height of a circumferential size intermediate that of the tip and band portion.

8. A hat block having its side and tip faces formed to meet at an acute angle at the tip edge, and having a metal tip edge provided by a metal ring set into the block with its outer surface flush with the adjacent surface of the block.

9. A hat block having its side and tip faces formed to meet at an acute angle at the tip edge, and having a metal tip edge provided by a metal edge ring.

10. A hat block having its side and tip faces formed to meet at an acute angle at the tip edge, and having the tip edge formed of a material having greater wear resisting qualities than the material of which the main portion of the block is formed.

11. A wooden hat block having a circumferential shaping edge formed of a material having greater wear resisting qualities than the material of which the main portion of the block is formed.

12. A hat block having a wooden body and an annular metallic band surrounding one end thereof and shaped into a sharp tip forming edge.

13. A hat block comprising a wooden body portion having a rabbet formed around one end thereof and a metallic rim set in said rabbet and shaped into a sharp tip forming edge.

14. A hat block having its sides straight in the direction from the lower to the upper portion of the block throughout the greater portion of the height of the block and formed to extend slightly outward at the tip beyond the adjacent portion of the sides.

15. A hat block for shaping square crown hats, having its sides vertically straight and inclined outward very slightly in the direction from the lower to the upper portion 105 of the block throughout the greater portion of the height of the block and having its tip edge extended slightly outward beyond the adjacent portion of the sides.

In testimony whereof, I have hereunto set my hand, in the presence of two subscribing witnesses.
